COMBINATION SADDLE PROTECTOR AND TAG HOLDER

Edwin M. Martin, 3215 9th St.,
Boulder, Colo. 80302

Filed Feb. 28, 1969, Ser. No. 15,979

Term of patent 14 years

Int. Cl. D30—03

U.S. Cl. D30—20

Fig. 1

Fig. 2

Fig. 3

FIG. 1 is a side view of the combination saddle protector and tag holder, showing my new design;

FIG. 2 is a top view thereof;

FIG. 3 is a side view, the other side being a mirror image thereof.

A representation of a saddle and display tag is depicted in dotted lines in FIG. 1 for purposes of illustration only.

I claim:

The ornamental design for a combination saddle protector and tag holder, as shown and described.
